(57) **CLAIM**

The ornamental design for a divided tray, as shown and described.

DESCRIPTION

FIG. 1 is a top perspective view of an embodiment of the divided tray.

FIG. 2 is a top plan view of the divided tray illustrated in FIG. 1.

FIG. 3 is a right elevation view of the divided tray illustrated in FIG. 1.

FIG. 4 is a left elevation view of the divided tray illustrated in FIG. 1.

FIG. 5 is a bottom plan view of the divided tray illustrated in FIG. 1.

FIG. 6 is a front elevation view of the divided tray illustrated in FIG. 1; and,

FIG. 7 is a back elevation view of the divided tray illustrated in FIG. 1.

The dashed lines in FIGS. 1–7 form no part of the claimed design for the divided tray.
